United States Patent Office.

R. A. STRATTON, OF PHILADELPHIA, PENNSYLVANIA.

Letters Patent No. 65,134, dated May 28, 1867.

IMPROVED MANGLE.

The Schedule referred to in these Letters Patent and making part of the same.

TO ALL WHOM IT MAY CONCERN:

Be it known that I, R. A. STRATTON, of Philadelphia, Pennsylvania, have invented an Improved Mangle; and I do hereby declare the following to be a full, clear, and exact description of the same, reference being had to the accompanying drawing, and to the letters of reference marked thereon.

My invention consists in the combination of three rollers with certain spring standards, which serve the twofold purpose of forcing the intermediate roller against the upper and border rollers, and of supporting and affording bearings for the journals of the three rollers. My invention also consists in the combination of the said three rollers with a shield for directing the clothes in the proper course.

In order to enable others skilled in the art to make and use my invention, I will now proceed to describe its construction and operation. On reference to the accompanying drawing, which forms a part of this specification—

Figure 1 is a front view of my improved mangle.

Figure 2, an end view.

Figure 3, a transverse section on the line 1-2, fig. 1; and

Figure 4, a longitudinal section of part of one of the rollers.

Similar letters refer to similar parts throughout the several views.

A is the base of the mangle, and to this base are secured the two frames or feet B and B', each of which is so constructed as to form sockets for the lower end of the two wooden standards D and D', which are permanently secured to each frame by a bolt, a. On the inside of the opposite standards D D are formed concave recesses for the reception of the journals b and b' of the rollers E and E', and on the inside of the standards D' D' are formed similar recesses for the reception of the journals d of the roller F. The standards D and D' at both ends of the machine are secured together at a point below the journals of the lowest roller E' by a bolt, f. The peculiar arrangement of the several rollers will be best observed in fig. 3, on reference to which it will be seen that the roller F is somewhat smaller in diameter than the rollers E and E', which are of equal diameters. It is not absolutely necessary, however, that the roller F should be smaller in diameter than the others, although I prefer it to be so, as it is the driving-roller; the handled fly-wheel h being secured to one of its journals, which projects beyond the standards, or an additional shaft may be used to carry a pinion gearing into a wheel on the projecting journal of the roller F. The peculiar arrangement of the rollers E E' and F has for its object the submitting of the clothes to be mangled to the machine in the direction of the red line x x, fig. 3, which is the most convenient arrangement for the attendant, who has simply to pass the article of clothing between the rollers E and F, when it will be directed between the rollers F and E' in the manner described hereafter, and fall thence, properly mangled, into any suitable receptacle on the floor or base of the machine. The pressure imparted to the clothes when thus passing between the rollers will depend upon two things: first, on the diameter of the roller F compared with the distance between the rollers E and E'; second, on the pressure imparted by the standards and bolts f to force the roller F between the rollers E and E'. For instance, if the diameter of the roller F be little greater than the distance between the rollers E and E', but little force need be exerted on it by the standards and screws f to obtain the desired pressure on the clothes. I have found the proportions and arrangement of the rollers, exhibited in fig. 3, to be advantageous in practice. In order that the clothes may, after passing between the rollers E and F, be directed between the rollers F and E', I make use of an endless apron, G, which passes round the rollers E and E', and between these rollers and the roller F; the clothes to be mangled passing between the latter roller and in contact with the apron. In order that this apron may not crowd to one end or the other of the roller, and in order that it may remain stretched and free from creases, I so stitch the opposite edges that it will be there contracted in length, so as to lap over the ends of the roller as seen at y, fig. 4, this contracting or reefing of the edges effectually preventing any lateral displacement or creasing of the apron, which, although to be preferred for various reasons, may be dispensed with and a permanent shield, m, introduced; as shown in fig. 3, for directing the clothes between the rollers F and E. As the standards D and D' are disconnected from the bolts f to their upper ends, they serve as springs to push the roller F between the rollers E and E', the rigidity and force of these springs depending on the adjustment of the bolts f, and as these springs readily yield to slight irregularities in the thickness of the object mangled, the operation of the machine is rendered uniform and easy.

As these standards serve the twofold purpose of supporting or affording bearings for the rollers, and forcing the intermediate roller between the upper and lower rollers, and as the usual weights and springs or other devices used for applying the desired pressure in ordinary mangles are dispensed with, it will be evident that my improved mangle possesses the advantages of simplicity and cheapness, while its efficiency is equal to that of more costly machines of this class.

I claim as my invention, and desire to secure by Letters Patent—

1. The combination of the rollers E E' secured to the adjustable spring standards D D', and the roller F secured to the spring standards D', the whole being constructed and arranged as and for the purpose set forth.
2. The shield m, arranged in respect to the rollers as and for the purpose described.

In testimony whereof I have signed my name to this specification in the presence of two subscribing witnesses.

R. A. STRATTON.
